WINDOW CONSTRUCTION

William R. Cordrey, Toledo, Ohio

Application November 15, 1948, Serial No. 60,068

1 Claim. (Cl. 20—52)

1

This invention relates to window-type of closures involving sash sections, whether screen or glass, and mounting frames therefor.

This invention has utility when incorporated in multiple sash carrying inverted U-shaped frames. Weather-strip slide providing legs may be used in the U-shaped frames, which may mount a double hung window and also a screen sash. The unit as a whole is adapted to be flush with its frame, and its frame is adapted to register with a building window frame to act as an additional or storm window for the building window frame.

Referring to the drawings:

Fig. 1 is a front view, partially broken away looking from the building outside toward the unit, of an embodiment of the invention in the building-insert or inverted U-frame portion thereof;

Fig. 2 is a section on the line II—II, Fig. 1, of the U-frame with dotted line showing of the building window opening in proximity thereto and into which the full-line unit is adapted to be inserted;

Fig. 3 is a perspective view on an enlarged scale of a fragment of a weatherstrip rib to be attached to the window sill between the U-legs of the frame as inserted in the building opening;

Fig. 4 is an edge view, with considerable portions broken away, of the three sash in their assembly relation and apart from the U-frame of Fig. 1;

Fig. 5 is a section on the line V—V, Fig. 1 showing the slide-guide for the sash and its assembly into the U-unit, with the edges of the sashes of Figs. 9 and 10 shown in dotted lines cooperating therewith;

Fig. 6 is an inside elevation of the upper glazed sash, a portion being broken away;

Fig. 7 is an inside elevation of the lower glazed sash;

Fig. 8 is an inside view of the screen sash, which showings of the several sash are on a reduced scale, and Fig. 5 enlarged;

Fig. 9 is an enlarged section on the line IX—IX, Fig. 6, being shifted to the left from the upper slide side of Fig. 5 with which it is adapted to be assembled; and

Fig. 10 is an enlarged section on the line X—X, Fig. 7, being shifted somewhat less to the left than Fig. 9 and accordingly closer to assembly relation with the lower slide side of Fig. 5.

A U-shaped frame, inverted, has a leg 1, a cross or upper end strip 2 and a leg 3 parallel to leg 1. A facing strip 4 may have a portion of its back or inner side 5 as a minor thickness portion to an offset 6, thereby providing a general L-shape in cross-section for the facing outside of the house. There is from this L-shaped element, a strip 7 spaced from the short or inner-leg by a metal plate 8. Screws 9 (see Fig. 5) through the strips 7 and the plate 8 enter the offset 6 in assembling the U-shaped frame as a unit.

2

The cross-over portion 2 at the inner side of its offset 6 has a groove 10. The plates 8 extend longitudinally substantially along the entire length of each side stile or leg 1 and 3 of the U-shaped frame. Each plate or strip 8 comprises two return bent portions bent around to face the side stile of the frame. One of the rebent portions 11 extends from the top of the frame down to about the center of the frame and is bent toward the outside of the frame. The other of the rebent portions 12 extends from the bottom of the frame up to about the center of the frame and is bent toward the inside of the frame. There may be a slight spacing 13 between the ends of the return bend portions 11, 12. These portions 11, 12, are at the free edge of the flat plate 8 remote from the plate mounting by the screws 9. In the frame, slightly downwardly from the bottom of the positioned upper sash, in each leg 1, 3, a screw 14 may mount a flat arm 15 having a flange 16 facing outwardly of the frame toward the sash, forming a hook or L-shaped member adapted as the flange 16 is swung outward to lie beyond the facing 4, to hold a sash, which may rest on a window sill 17, from falling outward. However, as such sash is up, the L-shaped members 15, 16, may be swung to lock such sash in its closed position. Openings 18, 19, in the legs 1, 3, may receive sash holding pins.

In Fig. 2 is shown in dotted lines a normal window-type opening in a building comprising a frame 20 with a stop 21 adapted to hold the upper sash 22 for vertical sliding in a way parallel to and outward from a similar way for a lower sash 23. Flush with its back face 5, the facing strips 4 of the U-shaped frame, at the ends join the end strip 2, and may have tongues or mortise tenons 24 to fit in back cut-outs or seats 25 of the face 5 ends of the strip 2. There may be a water-proof glue bond or other assembly means for the U-shaped frame as an assembled unit to have, say collared or flanged head screws 26 as detachable mounting means for one to install the frame as a storm-window holder.

A glazed storm window may have an upper sash comprising a pair of stiles 27 with a top rail 28 having an outwardly extending rib 29 to enter the U-shaped frame groove 10. The facing or inner sides of the rectangular sash frame may have a seat or ledge 30 to receive a glass 31 with holding means 32 (see Fig. 4). The outer sides of stiles 27 have two-step seats 33 with screws or fastening means 34 for slide L-shaped members 35. With the L-shaped members 15, 16, swung outward to clear the way for entrance of the top rail 28 of this storm sash 36, the flange overhang of the members 35 may be slid upward under the return bends 11 in thrusting the rib 29 into the groove seat 10. A check rail 37 to complete the lower side of the rectangle or upper sash 36, may then have the L-shaped members 15, 16, swung to have the flanges 16 seat snugly

in sustaining this sash 36 in fully closed upper position. Between the stiles 27, this check rail 37 lower side has a groove 38.

A second or lower glazed window sash 39 with stiles or slide sides 40 has a top check rail 41 complementary to the rail 37. The glazing seat or ledge 30' is here on the same side as a two-step seat 42 (see Fig. 10) in the stiles 40. L-shaped member slides 35' on this lower sash 39 are designed to coact with the return bends 12 in 10 thrusting the sash 39 downward and inwardly from the sash 36.

The sash 39 has a bottom rail 43 with a groove 43' (see Fig. 4) in its lower side or face with which may register a rib 44 (see Figs. 2 and 3) having anchoring means 45 with the sill 17 in extent between the free ends of the legs 1, 3, of the frame. There is thus provided a complete weather sealing assembly of the glazed sash 36, 39, as assembled in the U-shaped frame in its 20 mounting in a window opening of a building. The sash 39 has a ledge 30' for its glass 31' as held by means 32' therein.

The complete placing, removal and adjustment for the two sash 36, 39, may be accomplished from within the building. A finger seat 45' in the top rail 28 inner side may be engaged by the user in effecting the upward thrusting, and a withdrawable pin 46 at the seat 18 may supplementally hold the sash in the lifted closure position in the absence of or until the members 15, 16, are rocked into seating position. Furthermore, as the pin 46 is accessible only from within, it provides safety means against intruders. Finger seats 47 in the rail 43 enable the building occupant to shift this sash 39 to a desired open position. The sash 39 may be held in any open or closed position by cams 48 which may be swung to have shoes 49 frictionally grip the strips 21. In order for the one in the house to remove or adjust the inner lower storm sash 39, the cams 48 are released and the seats 47 engaged to lift the sash 39, even up to clear the slide rebent portions 12 so that the sash 39 may be easily removed. Once the sash 39 is removed then the L-shaped members 15, 16 may be easily reached and swung outwardly so that the flange 16 will project beyond the facing 4 of the frame. Then when the pins 46 are retracted, the upper sash 36 may be lowered past the L-shaped members 15, 16 and beyond the slide rebent portions 11 so that this upper sash may also easily be removed. Thus, the sashes 36 and 39 may be readily and conveniently handled for window cleaning and other attention.

A screen 50 is in a sash 51 with side stiles 52, top rail 53 with a rib 54 adapted to seat in the groove 38 of the sash 36 as this unit 51 is coplanar therewith and therebelow.

The screen sash 51 has a bottom rail 55 having finger seats 47' and bottom drain grooves 56 as facing the sill 17, so that as rain or window washing water is behind the sash 51, such may readily flow out therefrom. The bottom rail 55 (Fig. 4) has a ledge 30'' on which is holding means or stop 32'' for the screen 50. Pull pins 57 on the inner side of the screen 50 and thru the stiles 52 may enter the openings 19 of the U-shaped frame and thereby positively fix the screen in locked assembly position. Thus the 60 detachable screen sash 51 is mounted in the same plane as the upper sash 36 and forms therewith a flush outer facing for the assembly. The storm sash 39 may be clamp locked in partial or fully elevated position, for the desired screen expo-

sure in seasons when insects are prevalent. At the times when limited ventilation only is desired, the screen sash 51 may be left in, or removed, for the sash 39 may be adjusted, as to sash 22 or 23. In the event the sash 51 is removed, instead of stored thruout the year in its storm window assembly, then the storm window sash 36 may be lowered in the ventilation adjustment program. In fact, the sash dimensions may be such that the groove 54 may register in the groove 10, and the sash 36 removed entirely or merely placed below the screen to be held by pin or pins 46 in register with the openings 19.

Inasmuch as the multiple sash are fitted in the U-shaped frame 1, 2, 3, the overlap of the facing 5 is sufficient to adapt to a range of minor dimension variations. With the groove 43' to coact with the rib 44, there is effective weather sealing variance for a range of accurate fitting departures, even as out of true. This means that a relatively unskilled person, or householder, may install the U-shaped frame units, as not a cumbersome set-up. Then with such in place, the sash may be seated therein, left there permanently, and shifted or removed as one chooses. This ready range for handling is of advantage in painting upkeep, while its multi-season utility means that as left installed, there is not the occasion to take out, store and re-set.

What is claimed and it is desired to secure by Letters Patent is:

In a double hung window structure, a frame, two sliding sashes, a metal sash guide strip for said sashes extending longitudinally substantially along the entire length of each of the side stiles of said frame, said strips being attached to said side stiles and each strip comprising two return bent portions, one of said rebent portions extending from the top of the frame down to about the center of said frame and being bent toward the outside of said frame, and the other of said rebent portions extending from the bottom of said frame up to about the center of said frame and being bent toward the inside of said frame, both rebent portions facing the side stiles of said frame, said sashes having angle pieces attached to each of said side stiles of said sashes, said angle pieces riding in said rebent portions when the sashes are slid up and down.
